UNITED STATES PATENT OFFICE.

FRANK J. LE CLAIR, OF ATTLEBORO, MASSACHUSETTS, ASSIGNOR TO FREEMAN-DAUGHADAY COMPANY, OF CHARTLEY, MASSACHUSETTS, A CORPORATION OF MASSACHUSETTS.

COLLAR-HOLDER.

1,387,497.

Specification of Letters Patent. Patented Aug. 16, 1921.

Application filed May 17, 1921. Serial No. 470,358.

To all whom it may concern:

Be it known that I, FRANK J. LE CLAIR, a citizen of the United States of America, and resident of Attleboro, in the county of Bristol and State of Massachusetts, have invented new and useful Improvements in Collar-Holders, of which the following is a specification.

This invention concerns collar holders useful in retaining the edges of soft or unstarched collars in proper position about the neck of the wearer, and relates more particularly to that type of holder wherein clamping elements are provided for gripping and holding the material of the collar.

The principal object of the present invention is to improve the holding or gripping power of collar holders of the kind having gripping jaws or gripping elements for holding the corners of the collar without damage to the fabric of the collar. To this end, the collar holder is provided with gripping elements having elongated or extended gripping surfaces to insure a gripping area of very substantial extent, said gripping elements being so disposed as to lie in substantially parallel relation upon the insertion of the fabric of the collar between them, thus insuring a substantially uniform gripping pressure over the whole of the gripping surfaces.

To secure this result the opposed gripping elements are arranged normally out of parallelism so that when spread apart by the insertion of the collar they will assume the desired parallel relation.

A preferred embodiment of means for carrying the invention into effect is illustrated in the accompanying drawings in which,—

Figure 1 is a plan view of the holder showing the parts as in normal position before attachment to the collar;

Fig. 2 is a view similar to Fig. 1, but illustrating the device as secured to a collar;

Fig. 3 is a front elevation of the device of Fig. 1; and

Fig. 4 is a cross section taken on a line such as 4—4 of Fig. 1.

The holder as herein illustrated comprises a pair of bars 1, 2, secured together at their central portions by means of a clip 3 or in any other desired manner.

The bars 1, 2 are preferably of curved formation and of different radii of curvature, it being understood, however, that one

of such bars may be straight; that is to say, of infinite radius, if desired. The exact form of the bars is, however, of no particular consequence in so far as the present invention is concerned, providing the bars are so arranged that their outer portions diverge one from the other. At their outer ends, each of the bars is bent backwardly upon itself as indicated at 4, 5, respectively, to provide portions 6, 7 which lie substantially parallel to the main portions of the respective bars.

The portions 6, 7 are provided with offsets 8, 9, respectively which project toward the opposite bars, and formed as continuations of such offsets are the substantially straight and elongated clamping members 10, 11, respectively. Such members may, if desired, terminate in the outwardly flared elements 12, 13, such elements serving to avoid the tearing of the fabric in removing the same from between the clamping members. The members 10 and 11 which constitute the fabric clamping means are furnished with oppositely disposed gripping surfaces 14, 15, respectively, which are of substantial area and which may be roughened if desired, whereby to secure a better hold on the fabric.

The offset portions of the bars provide the open-ended guiding mouths 16 for directing the fabric into the space between the clamping elements 10, 11. One or both of the bars 1, 2 is resilient, such bars being illustrated herein as formed of substantially the same thickness of material and being equally resilient, and the parts are so disposed that in normal position the clamping members 10, 11 diverge from each other in a direction toward the center of the device, normally contacting with each other at the points 17 and being separated at their opposite ends as at 18. When, however, the collar fabric, indicated at C (Fig. 2) is inserted between the clamping jaws 10, 11, the gripping surfaces 14, 15 thereof assume a position of substantial parallelism one to the other whereby the entire surface of each gripping jaw may come into engagement with the fabric and bear with substantially uniform pressure thereover.

With this arrangement it is clear that by reason of the unusually large gripping surface provided and the fact that the co-operative clamping surfaces, when in engagement

with the fabric, lie substantially parallel one to the other, a very secure grip is obtained upon the fabric but without any tendency to injure or penetrate the same, such as may occur when gripping surfaces of small extent are employed.

While as herein disclosed, the clamping surfaces are indicated as roughened, such an arrangement is not necessary, as in view of 10 the large gripping area provided, a secure holding of the fabric may be obtained by the use of smooth jaws. It is also contemplated that, although the parallel gripping elements are shown as formed integral with 15 the bars, as by bending the ends of such bars into the proper shape, such gripping elements might be provided, if desired, by the use of members of proper contour secured in any desired manner to the bars, or that 20 such gripping elements might be formed integrally with the bars in other ways than by folding and bending portions of the latter.

Having thus described the invention in a preferred embodiment of the same, what I 25 claim and desire to secure by Letters Patent of the United States is:

1. A collar holder comprising a pair of oppositely disposed bars secured together at their central portions, one at least of said 30 bars being resilient, each of said bars having each of its end portions folded inwardly upon itself and constructed and arranged to provide an elongated and substantially straight gripping surface for coöperation 35 with the corresponding surface of the other bar, said coöoperating surfaces being normally disposed to diverge one from the other.

2. A collar holder comprising a pair of oppositely arranged resilient bars secured 40 together at their central portions, each end of each of said bars being folded inwardly upon itself for a short distance, and then offset toward the opposite bar, each of such offset parts including a substantially straight

portion providing a gripping surface of substantial extent for coöperation with the corresponding surface of the other bar, said surfaces being normally divergent but constructed and arranged to assume positions of substantial parallelism upon the insertion of 50 fabric therebetween.

3. A collar holder comprising a pair of resilient bars secured together at their central portions, each end of each bar having a portion folded back to lie substantially parallel to the bar and a portion in continuation of but offset from said folded portion, said offset portion being provided with a substantially flat and roughened gripping surface. 55

4. A collar holder comprising a pair of curved bars of different radii of curvature and secured together at their central portions, one at least of said bars being resilient, each end of each bar having a portion folded back upon itself and a portion in continuation of but offset from said folded portion and projecting toward the other bar, said offset portion comprising an elongated substantially straight gripping element, the opposed gripping elements of the two bars normally diverging one from the other in a 60 direction toward the center of the holder. 65

5. A collar holder comprising a pair of curved bars of different radii of curvature secured together at their central portions, 70 one at least of said bars being resilient, each end of each bar being bent back upon itself to form an elongated, substantially straight gripping element, the opposed gripping elements of the two bars normally diverging 75 one from the other in a direction toward the center of the holder and adapted to assume positions of substantial parallelism upon the insertion of the edges of a collar therebetween. 80

Signed by me at Attleboro, Massachusetts, 85 this 9th day of May, 1921.

FRANK J. LE CLAIR.
